ELECTRIC HOIST MOTOR STATOR MOUNT

Erford E. Robins, North Tonawanda, and Loren W. Lerch and Humphrey F. Parker, Buffalo, N. Y., assignors to Columbus McKinnon Chain Corporation, Tonawanda, N. Y.

Application December 13, 1955, Serial No. 552,939

4 Claims. (Cl. 310—258)

This invention relates to electric hoists, and more particularly to improvements in electric hoist frame and motor assemblies.

It is an object of the present invention to provide in an electric hoist an improved motor mounting arrangement.

Another object of the invention is to provide an electric hoist of improved design, whereby to facilitate relative assembly of the motor and the hoist frame.

Another object is to provide in an electric hoist construction improved means for anchoring the hoist motor stator in the hoist frame against motor torque reactions.

Other objects and advantages of the invention will appear in the specification hereinafter.

In the drawing:

Fig. 1 is an end elevational view, with portions broken away to show the interior construction, of a chain hoist embodying the invention; and

Fig. 2 is a fragmentary sectional view, taken along line II—II of Fig. 1.

As illustrated in the drawing, the invention may be embodied in an electric hoist construction including a die cast or otherwise fabricated hoist frame designated generally at 10, and arranged to be carried by means of a suspension hook 12, and having its load lift chain depending therefrom as indicated at 14. To drive the load lift wheel and the gear train furnishing power thereto, the hoist includes an electric motor comprising a stator sub-assembly 15 and an armature 16; the motor torque output shaft being indicated at 18. (Fig. 2.)

The present invention concerns the problem of mounting and anchoring the motor stator 15 in proper operative position within the hoist frame 10; and as illustrated herein, the purposes of the invention are accomplished by forming the frame or housing of the hoist in multi-sectioned form to include a main section as designated 20 which is internally bored to receive in slip-fitting relation therein (from the left hand end thereof as viewed in Fig. 2) the stator 15 of the hoist motor. The hoist frame portion 20 is provided with an abutment shoulder as indicated at 22 (Fig. 2) against which one end of the stator 15 lodges when it has been slip-fitted into the frame piece 20 to its proper depth. Adjacent its opposite end, the peripheral side wall of the stator 15 is provided with a radial bore or recess extending inwardly thereof to receive in firmly fitted relation therein an anchor pin 24. The recess and the pin are so relatively dimensioned that when the pin is fitted into the stator 15 it extends a substantial distance therefrom radially beyond the cylindrical wall of the stator as illustrated in the drawing.

The hoist frame section 20 is notched at its left hand peripheral edge portion in registry with the position of the pin 24 when the stator 15 is slip-fitted into the frame section 20 during the initial hoist assembly operation; the notched portion of the hoist frame being dimensioned to closely complement and embrace the extending portion of the pin 24 when the left hand side portion of the pin

registers with the left hand end portion of the frame section 20, as shown in Fig. 2.

The hoist frame structure is provided also to include an end cover component designated 26, having an open end rim portion at the right hand end thereof dimensioned to mate with and abut against the left hand end rim portion of the frame section 20 when the frame sections are in relative assembly as shown in Fig. 2. Machine screws as indicated at 28—28 or any other suitable means, are employed to lock the hoist frame components 20—26 together in assembled relation as shown in Fig. 2. Thus, it will be appreciated that upon locking of the end cover piece 26 against the frame section 20, the cover piece 26 will bear against the extending end portion of the pin 24 so as to prevent displacement thereof toward the left relative to the frame section 20, as shown in Fig. 2. Thus, the protruding end portion of the pin 24 is completely encompassed at all sides by the final frame assembly whereby the stator 15 is firmly anchored in proper position within the frame component 20 against movements relative thereto in any direction including rotation in response to torque reaction forces.

The frame section 26 is provided with a bearing device as indicated at 30 to support the left hand end portion of the motor shaft 18, while the right hand end portion of the motor shaft 18 is similarly supported in another bearing (not shown) carried within the hoist frame section 20, as is well understood in the art. Hence, by virtue of the frame construction of the present invention, the hoist components referred to hereinabove may be readily assembled by simply first slip-fitting the stator 15 in to the hoist section 20 to its operative position as shown in Fig. 2; then sliding the motor armature into position so that the right hand end portion of the motor shaft engages its bearing; and then sliding the end cover frame section 26 into position so as to simultaneously engage the bearing 30 upon the left hand end portion of the motor shaft 18 while bringing the right hand rim portion of the housing 26 into abutting relation against the frame section 20; thereby locking the anchor pin 24 interiorly of the hoist frame construction. As explained hereinabove, the machine screws 28—28 are then employed to maintain the frame parts in relative assembly. Thus, the cooperative frame parts provide the motor bearing mountings and firmly lock the anchor pin 24 in the hoist frame so as to thereby lock the motor in operative position in the frame. It will be appreciated that the construction of the invention as explained hereinabove may be fabricated by means of parts and shop methods of utmost simplicity, and that the construction facilitates initial assembly and subsequent disassembly and reassembly of the parts incidental to maintenance or repair operations.

Although only one form of the invention has been shown and described in detail, it will be apparent to those skilled in the art that the invention is not so limited but that various changes may be made therein without departing from the spirit of the invention or the scope of the appended claims.

We claim:

1. In an electric hoist, a frame including complementary shaped motor mount and cover frame sections adapted to be assembled in abutting aligned relation at opposed rim portions of the frame sections, a hoist motor slip-fitted into said motor mount frame section and having an anchor pin protruding radially therefrom, said motor mount frame section being notched to receive said protruding pin when the hoist motor is slip-fitted into said mount section while the protruding pin lies flush with the rim edge of said mount section, and means detachably interconnecting said mount section and said cover section whereby to lock them together in opposed

rim abutting engagement whereby said cover section is held in abutting engagement against on side of the protruding portion of said pin and whereby the protruding portion of said pin is completely encircled between said frame sections, said cover section including a bearing member engaging in slip-fitting relation the shaft of said motor when said frame sections are brought together.

2. In an electric hoist, a two-piece frame including mating motor mount and cover frame sections assembled in abutting aligned relation at opposed rim portions of the frame sections, a hoist motor stator slip-fitted into said motor mount frame section and having an anchor pin protruding radially therefrom, said motor mount frame section being recessed to receive said protruding pin in embedded relation therein when the hoist motor is slip-fitted into said mount section while the protruding pin lies flush with the rim edge of said mount section, and means locking said frame sections together in opposed rim abutting engagement whereby said cover section is held in abutting engagement against one side of the protruding portion of said pin and whereby the protruding portion of said pin is completely encircled between said frame sections, said cover section including a bearing member engaging in slip-fitting relation the shaft of said motor when said frame sections are brought together.

3. In an electric hoist, a two-piece frame including mating motor mount and cover frame sections adapted to be assembled in abutting aligned relation at opposed rim portions of the frame sections, a hoist motor slip-fitted into said motor mount frame section and having an anchor pin protruding radially therefrom, said motor

mount frame section being recessed to receive said protruding pin in embedded relation therein when the hoist motor is slip-fitted into said mount section while the protruding pin lies flush with the rim edge of said mount section, and means detachably interconnecting said mount section and said cover section whereby to lock them together in opposed rim abutting engagement whereby said cover section is held in abutting engagement against one side of the protruding portion of said pin and whereby the protruding portion of said pin is completely encircled between said frame sections.

4. In an electric hoist, a multi-part frame including mating motor mount and cover frame sections adapted to be assembled in abutting aligned relation at opposed rim portions of the frame sections, a hoist motor slip-fitted into said motor mount frame section and having an anchor pin slip-fitted into said motor and protruding radially therefrom, said motor mount frame section being notched to receive the protruding portion of said pin when the hoist motor is slip-fitted into said mount section while the protruding pin lies flush with the rim edge of said mount section, and means detachably interconnecting said mount section and said cover section whereby to lock them together in opposed rim abutting engagement whereby the protruding portion of said pin is completely encircled between said frame sections to lock the motor positionally within said frame, said cover section including a bearing member engaging in slip-fitting relation the shaft of said motor when said frame sections are brought together.
